(57) **CLAIM**

The ornamental design for a sunglasses clip holder, as shown and described.

DESCRIPTION

FIG. 1 is a bottom, front and left side perspective view of a sunglasses clip holder, showing my new design;

FIG. 2 is a top, back and left side perspective view thereof;

FIG. 3 is a front view thereof;

FIG. 4 is a back view thereof;

FIG. 5 is a left view thereof;

FIG. 6 is a right view thereof;

FIG. 7 is a top view thereof; and,

FIG. 8 is a bottom view thereof.

The broken lines shown in the drawings illustrate portions of the sunglasses clip holder and form no part of the claimed design.
